Primary Examiner — Omeed Agilee(74) Attorney, Agent, or Firm — Adibi IP Group, PC; Amir V. Adibi; Andrew C. Palmer(57) CLAIM

The ornamental design for a table with drop treatment portion, as shown and described.

DESCRIPTION

FIG. 1 is a perspective view of a table with drop treatment portion showing our new design.

FIG. 2 is a top view showing our new design.

FIG. 3 is a bottom view thereof.

FIG. 4 is a left side view thereof.

FIG. 5 is a right side view thereof.

FIG. 6 is an enlarged front view thereof.

FIG. 7 is an enlarged back view thereof; and,

FIG. 8 is a left side view of the table with the drop treatment portion engaged.

The broken lines depict portions of the table with drop treatment portion that form no part of the claimed design.
